US00D692923S

(12) **United States Design Patent**
Conrad et al.

(10) **Patent No.:** **US D692,923 S**
(45) **Date of Patent:** **** Nov. 5, 2013**

(54) **PUMP**

(71) Applicant: **Ingersoll-Rand Company**, Davidson, NC (US)

(72) Inventors: **John Conrad**, Troutman, NC (US); **Dale Tremel**, Charlotte, NC (US); **Amy Trochum**, Clinton, NJ (US)

(73) Assignee: **Ingersoll-Rand Company**, Davidson, NC (US)

(**) Term: **14 Years**

(21) Appl. No.: **29/443,156**

(22) Filed: **Jan. 14, 2013**

(51) LOC (9) Cl. **15-02**

(52) U.S. Cl.

USPC **D15/7**

(58) **Field of Classification Search**

USPC D15/7-9; D23/231, 232; 417/410.1, 417/359, 415-416, 234, 321, 265, 405, 1, 417/63, 53, 393; D24/107, 108, 111

(57) **CLAIM**

The ornamental design for a pump, as shown and described.

DESCRIPTION

Cross-reference is made to U.S. Utility patent application Ser. No. 13/741,057 entitled "Diaphragm Pump with Muffler-Mounted Sensor," which was filed by Dale Tremel et al. on Jan. 14, 2013 and is expressly incorporated herein by reference. FIG. 1 is a front perspective view of a design of a pump; FIG. 2 is a rear perspective view of the pump of FIG. 1; FIG. 3 is a front elevation view of the pump of FIG. 1; FIG. 4 is a rear elevation view of the pump of FIG. 1; FIG. 5 is a first side elevation view of the pump of FIG. 1; FIG. 6 is a second side elevation view of the pump of FIG. 1; FIG. 7 is a top plan view of the pump of FIG. 1; and, FIG. 8 is a bottom plan view of the pump of FIG. 1.

The broken lines shown in the figures depict environmental subject matter and form no part of the claimed design.

1 Claim, 8 Drawing Sheets
